AEROSOL SPRAY CAN DEACTIVATOR

Roy L. White, Hutchinson County, Tex.
(8 Sands St., Phillips, Tex.)

Filed Apr. 20, 1965, Ser. No. 84,875

Term of patent 14 years

(Cl. D54—13)

FIG. 1

FIG. 2

FIG.3

FIG.4

FIGURE 1 is a top front oblique perspective view of an aerosol spray can deactivate showing my new design; FIGURE 2 is a view as in FIGURE 1 during operation thereof;

FIGURE 3 is a top view of my design;

FIGURE 4 is a front elevation view thereof.

The broken lines are shown for illustrative purposes only.

I claim:

The ornamental design for an aerosol spray can deactivate, as shown,
